Primary Examiner — S. Bryan Reinholdt, Jr.(74) *Attorney, Agent, or Firm* — Preston P. Frischknecht; Project CIP(57) **CLAIM**

The ornamental design for a container lid as shown and described.

DESCRIPTION

FIG. 1 is a first perspective view of the container lid design; FIG. 2 is a first side view thereof;

FIG. 3 is a second side view thereof;

FIG. 4 is a third side view thereof;

FIG. 5 is a fourth side thereof;

FIG. 6 is a top view thereof;

FIG. 7 is a bottom view thereof; and,

FIG. 8 is a third perspective thereof in an alternate position of use.

The dashed lines depict portions of the container lid that form no part of the claimed design. The stippling depicts portions of the container lid with a texture that is part of the claimed design.

1 Claim, 8 Drawing Sheets(56)
